UNITED STATES PATENT OFFICE.

HARRY INGRAHAM LAVERS, OF WEST SOMERVILLE, MASSACHUSETTS.

WORK-HOLDING CLAMP.

1,353,353.

Specification of Letters Patent. Patented Sept. 21, 1920.

Application filed November 26, 1919. Serial No. 340,856.

To all whom it may concern:

Be it known that I, HARRY INGRAHAM LAVERS, a citizen of the United States, and a resident of West Somerville, in the county 5 of Middlesex and State of Massachusetts, have invented certain new and useful Improvements in Work-Holding Clamps, of which the following is a specification.

My invention relates generally to work 10 holding clamps, and particularly to a clamp for holding portions of carpenter or cabinet work together until the glue used for uniting the same has become sufficiently set.

It is a purpose of my invention to provide 15 a clamp of this character which is of simple and efficient construction, and in which means is provided for clamping a piece of work and forcing another piece of work into proper position with relation to the first 20 piece of work, such means being operable by a single element so that the two functions are performed simultaneously.

I will describe one form of clamp embodying my invention and will then point 25 out the novel features thereof in claims.

In the accompanying drawings:—

Figure 1 is a view, showing in perspective two pieces of work having applied thereto 30 one form of clamp embodying my invention;

Fig. 2 is a longitudinal section of the clamp in its applied position upon the work;

Fig. 3 is a transverse sectional view, taken on the line 3—3 of Fig. 2; and

Fig. 4 is a similar view, taken on the line 4—4 of Fig. 2.

Referring specifically to the drawings, in which similar reference characters refer to similar parts, P and P' designate a pair 10 of plates of substantially U-shaped formation which are secured together in spaced parallelism by pins 15 and 15^a and rods 16 arranged at the forward and rear ends of the plates, respectively. At points between 5 the plates P and P' the rods 16 are provided with tubular sleeves 16^a for the purpose of maintaining the rear ends of the plates in proper spaced relation. Fulcrumed upon the pins 15 and 15^a at points intermediate 0 their ends are a pair of jaws J and J' which are preferably formed of wood. The forward ends of the jaws J and J' are inturned and covered with sheets of soft material such as rubber or the like to prevent 5 ring of the work by the jaws. The rear ends

of the jaws or those ends disposed between the plates P and P' are recessed upon their confronting faces to provide inclined surfaces 18 between which is adapted to work an expanding member M. As shown in Fig. 60 2, the expanding member is of wedge shaped formation and as shown in Fig. 4 the top and bottom walls thereof are formed with tongues 19 which work in grooves 20 formed in the inclined faces 18. The front side of 65 the expanding member is recessed to receive a nut 21 and extending through the latter and the member is a screw threaded shaft 22. The forward end of the shaft 22 is provided with a foot 23, while its rear end is 70 formed with a crank 24 which is adapted to be operated by a handle 25.

In the applied position of the clamp, as shown in Figs. 1 and 2, one piece of work A is placed between the parallel portions of 75 the plates P and P' and between the jaws J and J' with one edge of the work bearing against the foot 23. The other piece of work A' which is adapted to be glued to the piece A is properly positioned with relation to the latter and is interposed between 80 the outer ends of the jaws J and J'. With the clamp in this position, it is obvious that upon rotation of the shaft 22 a forward feeding of the same is effected by its coaction with the nut 21 thereby forcing the piece of work A in the direction of the piece of work A'. Simultaneously with this movement, a rearward movement of the expanding member is effected, and because of 85 90 the contour of the member and the inclined surfaces 18, it is obvious that an outward movement of the adjacent ends of the jaws is effected to cause their forward ends to securely grip the piece of work A'. In this 95 manner the two pieces of work are forced together and securely held until the glue has become sufficiently set, whereby an efficient uniting of the work is effected. It will be understood that the clamp may be readily 100 removed from the work by rotating the shaft 22 in the opposite direction so as to move the foot 23 out of engagement with the piece of work A and to cause a forward movement of the expanding member, thereby 105 permitting the forward ends of the jaws to disengage the piece of work A'.

Although I have herein shown and described only one form of clamp embodying my invention, it is to be understood that 110

various changes and modifications may be made herein without departing from the spirit of the invention or the spirit and scope of the appended claim.

5 Having thus described my invention, I claim:

A clamp comprising a pair of U-shaped plates, a pair of jaws fulcrumed between said plates, one of the ends of said jaws 10 having their confronting faces recessed to

provide oppositely inclined surfaces, a block interposed between said ends and having sliding engagement with said surfaces, a nut carried by said block, a screw threaded shaft extending through said block and 15 threadedly engaging said nut, a foot carried by said shaft, and a crank for actuating the shaft.

HARRY INGRAHAM LAVERS.
